3 Sheets-Sheet 3

UNITED STATES PATENT OFFICE

JOHN L. McMILLAN, OF SYRACUSE, NEW YORK, ASSIGNOR TO Mc MILLAN BOOK COMPANY, OF SYRACUSE, NEW YORK, A CORPORATION OF NEW YORK

LOOSE-LEAF BINDER

Application filed March 14, 1928. Serial No. 261,532.

This invention relates to a new and improved loose leaf binder in which the sheets are retained in position on prongs or arcuate posts and is particularly directed to that type of binder in which the sheets may be moved from one set of prongs to another without the necessity of removing the sheets from the prongs.

In using loose leaf binders it is frequently desirable that they be so arranged that they may be used for the keeping of the accounts of different individuals in such a way that the placing of the sheets in the binder with reference to one another will result in providing a visible index of the several accounts on the sheets. When a book is being used for this purpose the length of the sheets is usually considerably less than the height of the book so that a sheet may be positioned on different prongs and still remain within the covers of the book. When a book is being put to this use in which the sheets are assembled on different prongs so that all the titles of the accounts will be visible it is frequently desirable to remove one of the sheets from the book when, for example, the particular account represented on that sheet has been closed or for some other reason. When this occurs the sheets in the book below the one removed will all be moved one prong upwardly so that a new sheet may be inserted in the book as the bottom sheet.

In order to accomplish the transfer of sheets in the manner just described it is very desirable that some means be provided whereby a plurality of sheets may be moved in one operation and without actual removal of the sheets from the prongs and the main object of my invention is to provide a means whereby the opposed prongs in the book may be so changed in relation to each other that sheets may be transferred from one set of prongs to another set of prongs while at the same time the sheets are at all times retained on prongs.

Another object is to provide a means whereby this result may be accomplished without the necessity of moving any part of the apparatus outside of the main body of the book.

Other objects and advantages relate to the

size, shape and arrangement of parts all as will more fully appear from the following description taken in connection with the accompanying drawings in which:

Figure 1 is a perspective view of my improved book in the closed position. 55

Figure 2 is an end view of the prong carrying mechanism of my device in the closed position.

Figure 3 is a view similar to Figure 2 with the device in the intermediate position. 60

Figure 4 is a view similar to Figure 2 with the device in the open position.

Figure 5 is a section on line 5—5 of Figure 1. 65

Figure 6 is a top plan view of the device in the position shown in Figure 3.

Figure 7 is a section on line 7—7 of Figure 2.

Figure 8 is a bottom plan view of a section 70 of one of the back members.

Figure 9 is a view of a modified form of structure with the book partially open and the prongs in position for shifting sheets.

Figure 10 is a section on line 10—10, Figure 75 12.

Figure 11 is a section on line 11—11, Figure 10.

Figure 12 is a section on line 12—12, Figure 90 9.

Figure 13 is a view of a broken away section of a back member as used in the structure of Figures 9, 10, 11 and 12.

My device, as shown in Figures 1 to 8 inclusive, consists of back-members —1— and —2— of wood, metal, or other suitable material, and being positioned in parallel relation and hingedly connected by hinges —3— and —4—. I provide for use with back member —1— a plurality of prongs —5—, each consisting of a curved upper portion —6—, an upright side portion —7—, and a horizontal bottom portion —8— beneath the top portion —6—. The prongs —5— are mounted for rocking movement in spaced relation with their upright portions —7— seated in bearings or vertical channels —60— in the outside edge of back member —1—, and have their bottom portions —8— positioned in recesses —9—, which may be of V-shaped form, in 100

the bottom wall of back member —1— to permit limited swinging movement of parts —8— when the upright portions —7— of prongs —5— are rotated.

I also provide a bar —10— extending longitudinally of back member —1— and positioned in a slot —61— formed in back member —1—, which permits relative sliding movement between bar —10— and back member —1—. Bar —10— is provided with holes or openings through which the ends of portions —8— of prongs —5— extend so that the movement of one of the portions —8—, or the rocking of one of prongs —5— will cause a similar movement of all of the other prongs —5—, thereby effecting a swinging movement of portions —6— conforming with the swinging movements of the portions —8— of prongs —5—.

I also provide in bar —10— depressions —11—11— for the reception of a detent —12— which is positioned in back member —1— and which consists of a plunger —13— backed by a spring —14— so that the entrance of plunger —14— into one of the depressions —11— will yieldingly hold bar —10— in a selected position. I further provide a back-plate —15— extending along the outer longitudinal edge of back-member —1— and secured thereto by screws 16 or other convenient means, for the purpose of holding prongs 5—5 in position in the bearings or channels —60— in the outer edge of member —1—. An angular cover plate —17— is positioned on the upper surface of back member —1— along the outer longitudinal edge thereof with its upright portion against the inner surface of the upright portions 7—7 of prongs 5—5. Cover plate —17— has its upper edge bent outwardly and downwardly to lock on the upper edge of back plate —15— and is provided with a plurality of holes 18—18 for the reception of prongs 5—5 and is also provided with a plurality of holes 19—19 positioned between the edges of the adjacent prongs 5—5 midway between them and in line with holes 18—18. A locking plate —20— is positioned on the upper surface of back member —1— with its outer edge superposed on the lower horizontal portion of locking plate —17— and is held in position by screws 21—21 or other convenient means. A plurality of hinge members 22—22 are affixed by welding or other convenient means to the outside face of back plate —15— which members 22—22 register with a hinge member —23— affixed to a book cover —24— and held in hinged relation thereto by means of a pintle —25—. A guide plate —38— is positioned on the under surface of back member —1— extending longitudinally thereof to retain in place and act as a guide for the bar —10—.

Back member —2— is provided with a back plate —26— affixed to the outer longi-

tudinal edge thereof by screws, not shown, or other convenient means and has affixed thereto by welding or other convenient means a plurality of prongs —27— held in spaced relation by means of spacing plates 28—28, the position of rings 27—27 on back member —2— being in staggered relation to the position of prongs 5—5 in back member —1—. A locking plate —29— angular in shape is positioned on the upper surface of back member —2— along the outer longitudinal edge thereof and abutting against the inner faces of prongs 27—27.

Locking plate —29— has its upper edge bent outwardly and downwardly on to the edge of locking plate —29—. The upper edge of locking plate —29— is provided with a plurality of openings 30—30 through which extend prongs 27—27, and is also provided with a plurality of openings 31—31 positioned between adjacent prongs 27—27 midway thereof, and aligned with holes 30—30. A top plate —32— is positioned on the upper surface of back member —2— and the lower horizontal portion of locking plate —29— and is held in position by screws 33—33 or other convenient means.

A plurality of hinge members —34— are affixed to back plate —26— by welding or other convenient means, and are in registration with a hinge member —35— in a cover —36— being held in hinged relation thereto by a pintle —37—.

The position of prongs 5—5 in back member —1— in relation to holes 31—31 in locking plate —29— is such that when the book is in the closed position the ends of prongs 5—5 will register with and enter holes 31—31. Similarly the prongs —27—27 in back member —2— are so positioned with relation to holes —19— in back member —1— that when the book is in closed position the ends of the prongs 27—27 will register with and enter holes 19.

The length and position of prongs —5— in relation to prongs —27— is such that when the book is in an intermediate open position and the prongs —5— are rotated or swung in either direction about their upright portions —7—, the ends of the prongs —5— will be moved or shifted a distance either upwardly or downwardly of the book equal to the distance between the centers of two adjacent perforations in a sheet of paper adapted to be used in the book, as illustrated in Figure 9 at A.

It will be understood that prongs —5— may be swung in either direction, rendering them capable of use in shifting sheets either up or down in the book, and as the prongs are capable, in this embodiment of a maximum swinging movement covering a distance twice as great as the distance between two apertures in a sheet, it will be apparent that the book is capable of operation for shifting a sheet

either one aperture at a time, or two apertures at a time, should the latter be desired.

Shifting a sheet two apertures at a time may be accomplished by first moving the sheet from the movable set of prongs to the stationary set of prongs. Then by swinging the prongs —5— in one desired direction and then shifting the sheets back to the movable prongs —5—, and then swinging the prongs from their shifted position first to a normal position, as illustrated in Figure 6, and then swinging them to the opposite side of their normal position, when the sheets are shifted to the stationary prongs —27— they will have been moved upwardly in the book two perforations.

The reverse operation of shifting the sheets downwardly in the book either one or two apertures is effected by reverse operation of the prongs —5—. Shifting of sheets one aperture at a time is readily effected if the sheets are mounted upon the movable prongs —5— by swinging the prongs in either direction, as desired, shifting the sheets from the movable prongs —5— to the stationary prongs —27—, then swinging the prongs —5— back to neutral position, and shifting the sheets back to the movable prongs —5—. Various methods of operation in shifting the sheets may be utilized in connection with the structure disclosed.

The shoulders or walls —62— at opposite sides of recesses —9— constitute stops against which the portions —8— of the prongs —5— abut and the movement of the prongs in either direction from neutral position, as limited by these shoulders, is just sufficient to effect shifting of a sheet one aperture at a time.

End plates —41— are affixed by rivets, (not shown) or other convenient means, to each end of back member —2—, and as they are similar in design, the description of one is a description of both. End caps —41— may be of a shape to conform to the end contours of the formed frame and extend upwardly from back-member —2— to approximately the upper end of locking plate —29—. End plates —41— are provided with slots —42— for a purpose hereinafter to be described.

Locking plates —43— are rigidly secured to the opposite ends of a rod —44— which extends through back member —2— and which is journaled at opposite ends in end plates —41— in such a manner that locking plates —43— are positioned adjacent the outer faces of end plates —41—. Locking plates —43— are similar in shape, and function, and a description of one is a description of both. Plates —43— are provided at one end with an outwardly extending tab —45— adjacent end plates —41— and carry inwardly extending tongues —46— which extend through slots —42—. The opposite ends of locking plates —43— are provided with an elongated slot

—47— having recesses —48—, —49— and —50— for the reception of lug —40—. Locking plates —43— are also provided with rectangular holes —51— for a purpose hereinafter to be described. Springs —52— are mounted on the inner faces of end plates 41 and engage tongues 46 to yieldingly hold lug 40 in one or the other recesses —48—, —49— and —50—.

The outer and bottom longitudinal faces of back members —1— and —2— are provided with finish strips —53— and —54— respectively. In the closed position of my book, prongs 5—5 will have their ends positioned in holes —31—31 and prongs —27— will likewise have their ends positioned in holes —19—. In this position of the book the relative position of end plates 39 and 41 and locking plates 43 will be, as shown in Fig. 2 with lug —40— in recess 48 to lock the members in that position.

If it is desired to transfer sheets from one set of prongs to another, one end of locking plate —43— is depressed by means of tab —45— against the action of spring —52— to release lugs —40— from recesses —48— and permit locking plates 43 to move in relation to end plates —39— until lugs —40— are positioned in recesses 49 to lock the book in the intermediate position. The relative position of the parts, when the book is in the intermediate position, may best be seen from Figs. 3 and 6. It will be understood that the depression by means of a tab —45— of the end of one locking plate —43— will cause a similar movement of the other locking plate —43— due to the fact that they are both rigidly secured to the rotatable rod —44—. In the intermediate position just described, the rectangular openings —51— in locking plates —43— will register with the ends of bar —10— to permit its movement therethrough.

If it is desired to remove sheets from the prongs, or place additional sheets thereon, the book is placed in the open position, as indicated in Figure 4, by depressing tabs —45— to release lugs —40— from recesses —49— and permit their entrance into recesses —50— to lock the book in the open position.

The size and position of openings —51— in locking plates 43 is such that when the book is in the closed position, as indicated in Figure 2, or in the open position, as indicated in Figure 4, the bar —10— will not register with the openings 51, and the prongs —5— cannot be moved from their normal position. The opening of the book is assisted by a spring —56— positioned on hinge —4— and exerting pressure to open hinge —4—. The closing of the book is accomplished by moving back members —1— and —2— towards each other, which will cause tongues —46— to move to the bottom of slots —42— and any further movement of

locking plates —43— then being prevented, the lugs —40— will move from recesses —50— and —49— into recess —48— to lock the book in the closed position.

5 The structure shown in Figures 9 to 13 inclusive is similar in construction and operation to the structure heretofore described, except that the movable prongs —5— instead of swinging about the so-called vertical portions —7— are arranged to swing about the so-called horizontal portions —8— as a substantially fixed axis. This is accomplished as perhaps best shown in Figures 12 and 13 by inserting the portions —8— of the prongs 10 in conduits or openings in the back member —1—, such openings constituting journals within which the portions —8— of the prongs may rotate. Rotation of the portions —8— in these bearings in the back member —1— is permitted by the fact that the outer edge of the back member is formed with a recess —65— which may, as shown, 15 extend upwardly from the conduit or opening —66— to the upper surface of the back member, and as illustrated is substantially 20 V-shape in form, and flares upwardly to permit the section —7— of the prong to swing therein a limited distance upon each 25 side of the normal position, the walls of the recess constituting stops limiting the 30 swinging movement of the prong preferably to such an extent that the prong moves a distance just sufficient to permit shifting of a sheet one perforation at a time. As the prong 35 can be shifted this distance upon both sides of the normal position, it in like manner as heretofore described, permits the shifting 40 of a sheet two perforations at a time, if that is desired.

45 For the purpose of moving all of the prongs —5— in Figures 9 to 13 simultaneously, the bar —67— is provided mounted in a recess —68— in the back member —1— and confined therein by the angular plate —17— and having recesses for receiving the respective portions —7— of the prongs, as perhaps 50 best illustrated in Figures 10 and 11 so that movement of one prong will effect simultaneous movement of all of the prongs through a uniform distance.

55 In general, the operation of the two structures described is substantially the same, as a swinging movement of the prongs of one set permits shifting of properly perforated sheets through a distance of either one perforation or two, as may be desired.

60 The broad claims directed to the means for maintaining the back members in various positions of adjustment about their hinging connection, are retained as subject matter for one of my copending applications.

65 It will be understood that the length of the sheets to be used in my device may be varied at will, it only being necessary to provide sheets having holes, or perforations, there-

through properly positioned for the reception of prongs —5— and —27— and it will also be understood that the materials of which my device is constructed may be varied, as desired, without departing from the spirit of my invention, for altho I have shown and described specific structures and forms of parts as an exemplification or an embodiment of my invention, I do not desire to restrict myself to the exact size, shape and arrangement of parts, as various changes may be made within the scope of the appended claims.

I claim:

1. In a loose leaf binder adapted to contain record leaves, two series of impaling prongs, means for mounting and guiding the series of impaling prongs for movement away from each other to permit removal or addition of record leaves, and means pivotally mounting the impaling prongs of one series for movement to dispose the same angularly with respect to the impaling prongs of the other series and effect longitudinal shifting of said leaves with reference to each other.

2. In a loose leaf binder adapted to contain record leaves, two series of impaling prongs, means for mounting and guiding the series of impaling prongs for movement away from each other to permit removal or addition of record leaves, means mounting the impaling prongs of one series for angular movement to shift their free ends with respect to the impaling prongs of the other series and effect longitudinal shifting of said leaves with reference to each other, and means operable to secure said last-mentioned series of impaling prongs against movement.

3. In a loose leaf binder adapted to contain record leaves, two series of impaling prongs, means for mounting and guiding the series of impaling prongs for movement away from each other to permit removal or addition of record leaves, means mounting the impaling prongs of one series for angular movement to shift their free ends with respect to the impaling prongs of the other series and effect longitudinal shifting of said leaves with respect to each other, means operable to secure said last mentioned series of impaling prongs against movement, and means for securing the series of impaling prongs against transverse movement.

4. A loose leaf book comprising a pair of back members, a set of prongs carried by one of said back members, and a set of prongs carried by the other member, hinging means connecting said back members to permit movement of said sets of prongs toward and from each other, the prongs of one of said sets being shiftable obliquely about substantially fixed axes in two directions from their normal transverse position to dispose the prongs of the shiftable set angularly with

respect to the normal transverse plane of such prongs.

5. A loose leaf book comprising a pair of back members hingedly connected together, a set of prongs carried by one of said back members, a set of prongs carried by the other member, the prongs of one of said sets being shiftable obliquely about substantially fixed axes in two directions from their normal 10 transverse position to vary their position with respect to the prongs of the other set, and means for maintaining the body members in different positions of adjustments in their relative hinging movement.

15. 6. In a loose leaf binder adapted to contain record leaves, a pair of back members, opposed sets of prongs mounted on respective back members, hinging means connecting the back members for relative movement about 20 a longitudinal axis to move the sets of prongs toward and from each other to permit removal and insertion of leaves, means for independently pivoting the prongs of one set each upon a separate axis to permit angular 25 movement of said pivoted prongs with respect to the normal lengthwise planes of the prongs of the other set, and means for simultaneously effecting pivotal movement of said pivoted prongs.

30. 7. In a loose leaf binder adapted to contain record leaves, a pair of opposed back members, hinging means connecting the back members for relative movement about a longitudinal axis, a plurality of prongs mounted 35 on each back member for movement toward and away from each other about said hinging means, and means for moving the prongs on one back member obliquely with respect to the normal lengthwise planes of the prongs 40 on the other back member to facilitate longitudinal shifting of said leaves with reference to each other.

45. 8. A loose leaf binder adapted to contain record leaves comprising opposed sets of prongs, a prong-supporting member for each set, said members being relatively movable in reverse directions to move the sets of prongs toward and from each other, and means for adjusting the prongs of one member 50 diagonally with respect to the plane of their opening and closing movements.

55. 9. A loose leaf binder having opposed prong-supporting members, each having a plurality of prongs normally parallel with the prongs of the other member and relatively movable toward and from each other to open and close the binder, and means for shifting the prongs of one set to and from planes parallel with the planes of the prongs 60 of the opposite set.

65. 10. A loose leaf binder having opposed prong-supporting members, each having a plurality of prongs normally parallel with the prongs of the other member and relatively 70 movable toward and from each other to open

and close the binder, and means for shifting the prongs of one set in either of two directions to and from their normal planes parallel with the planes of the prongs of the opposite set.

70. 11. A loose leaf binder having opposed prong-supporting members, hinging means connecting said members for relative movement about a longitudinal axis, a set of prongs mounted upon each of said members, the prongs of one set being normally parallel with those of the other set and relatively movable toward and from each other about said hinging means to open and close the binder, and means for shifting the prongs 75 of one set to and from planes parallel with the planes of the prongs of the opposite set.

80. 12. A loose leaf binder having opposed prong-supporting members, hinging means connecting said members for relative movement about a longitudinal axis, a set of prongs mounted upon each of said members, the prongs of one set being normally parallel with those of the other set and relatively movable toward and from each other about said hinging means to open and close the binder, and means for shifting the prongs 85 of one set in either of two directions to and from planes parallel with the planes of the prongs of the opposite set.

90. 13. A loose leaf binder adapted to contain record leaves comprising two sets of impaling prongs, a back member mounting one set of impaling prongs, a second back member, means for individually pivoting the prongs of the other set upon said second back member to permit angular movement of said prongs upon their separate axes with respect to the prongs of the other set, and means connecting the back members for relative movement to carry the sets of prongs away from each other to permit removal or insertion of leaves.

95. 14. A loose leaf binder adapted to contain record leaves comprising two sets of impaling prongs, a back member mounting one set of impaling prongs, a second back member, means for individually pivoting the prongs of the other set upon said second back member to permit angular movement of said prongs upon their separate axes with respect to the prongs of the other set, means connecting the back members for relative movement to carry the sets of prongs away from each other to permit removal or insertion of leaves, 100 and means for holding said back members in an intermediate position of adjustment between the limits of their relative movement.

105. 15. In a loose leaf binder adapted to contain record leaves comprising two back members and hinging means connecting said back members for relative movement about a longitudinal axis, a set of prongs carried by one back member, a plurality of separate journals on the other back member, a prong mounted 110

in each of said journals and rotatable therein to and from parallel relation with the prongs of the other set.

16. A loose leaf binder adapted to contain record leaves comprising two sets of impaling prongs normally disposed parallel to each other, a back member mounting one set of impaling prongs, a second back member, means for individually pivoting the prongs of the other set upon said second back member to permit angular movement of said prongs upon their separate axes to and from their normal parallel relation to the prongs of the other set, and hinging means connecting the back members for relative movement to carry the sets of prongs away from each other to permit removal and insertion of leaves.

17. A loose leaf binder adapted to contain record leaves comprising two back members, hinging means connecting said back members for relative movement about a longitudinal axis, a set of prongs carried by one back member, a plurality of separate journals on the other back member, a prong mounted in each of said journals and rotatable therein to and from parallel relation with the prongs of the other set, and means connecting the rotatably mounted prongs to effect their simultaneous rotatory movement.

18. In a loose leaf binder adapted to contain record leaves, a pair of back members, hinge means connecting said back members for relative movement about a longitudinal axis, a series of prongs carried by each member and normally extending parallel with each other, the prongs of each series extending in closed position of the book from one back member to the other back member, said series of prongs being relatively shiftable to and from overlapping position by movement of said back members about said hinge, and means for shifting the prongs of one series to and from planes parallel with the planes of the prongs of the opposite series to permit longitudinal shifting of said leaves with reference to each other.

19. In a loose leaf binder adapted to contain record leaves, a pair of back members, hinging means connecting said back members for relative movement about a longitudinal axis, opposed sets of prongs carried by said back members for movement toward and from each other about said hinging means and means mounting one of said set of prongs upon its back member permitting movement of the prongs of said set about axes disposed at substantially right angles to the axis of said hinge.

20. In a loose leaf binder adapted to contain record leaves, a pair of back members, hinging means connecting said back members for relative movement, a set of prongs carried by each back member, the prongs of one of said sets being shiftable about axes disposed

at right angles to the axis of said hinging means.

21. In a loose leaf binder adapted to contain record leaves, a pair of back members, hinging means connecting said back members for relative movement about a longitudinal axis, opposed sets of prongs carried by said back members for movement toward and from each other about said hinging means, means mounting one of said sets of prongs upon its back member permitting movement of the prongs of said set about axes disposed at substantially right angles to the axis of said hinge, and means for holding the back members in an intermediate position of adjustment between the limits of their respective hinging movement with the ends of the prongs of one set slightly overlapping the ends of the prongs of the other set.

22. In a loose leaf binder adapted to contain record leaves, a pair of back members, hinging means connecting said back members for relative movement, a set of prongs carried by each back member, the prongs of one of said sets being shiftable about axes disposed at right angles to the axis of said hinging means, and means for holding the back members in an intermediate position of adjustment between the limits of their respective hinging movement with the ends of the prongs of one set slightly overlapping the ends of the prongs of the other set.

23. In a loose leaf binder adapted to contain record leaves, a pair of back members, hinging means connecting said back members for relative movement about a longitudinal axis, opposed sets of prongs carried by said back members for movement toward and from each other about said hinging means, means mounting one of said sets of prongs upon its back member permitting movement of the prongs of said set about axes disposed at substantially right angles to the axis of said hinge, and a slidably mounted bar connected to each of the shiftable prongs for effecting their simultaneous shifting movement.

24. In a loose leaf binder adapted to contain record leaves, a pair of back members, hinging means connecting said back members for relative movement about a longitudinal axis, a set of prongs carried by each back member, the prongs of one of said sets being shiftable about axes disposed at right angles to the axis of said hinging means, and a slidably mounted bar connected to each of the shiftable prongs for effecting their simultaneous shifting movement.

25. In a loose leaf binder adapted to contain record leaves, a pair of back members, hinge means connecting said back members, a plurality of leaf-retaining members carried by one of the back members and arranged in longitudinally spaced relation, a plurality of leaf-retaining members independently piv-

oted on the other back member and being positioned intermediate the first mentioned leaf-retaining members, and all of said leaf-retaining members being normally disposed in substantially parallel planes and extending in closed position of the book from one back member to the other back member, the pivotally mounted set of prongs being shiftable angularly out of said planes parallel with the planes of the prongs of the other set to permit longitudinal shifting of said leaves, and said back members being movable about their hinged connection to move the prongs to and from overlapping position.

26. In a loose leaf binder adapted to contain record leaves, a pair of back members, hinge means connecting said back members, a plurality of leaf-retaining members carried by one of the back members and arranged in longitudinally spaced relation, a plurality of leaf-retaining members independently pivoted on the other back member and being positioned intermediate the first mentioned leaf-retaining members and being shiftable about their pivots to and from their normal parallel relation with the prongs of the other set to permit longitudinal shifting of said leaves, and said back members being movable about their hinge connection to a closed position where the prongs on each back member extend across to the other back member, and said back members being movable about said hinge to an intermediate position to permit shifting of said leaves without their removal from the book.

27. In a loose leaf binder adapted to contain record leaves, a pair of back members, hinge means connecting said back members, a plurality of leaf-retaining members carried by one of the back members and arranged in longitudinally spaced relation, a plurality of leaf-retaining members independently pivoted on the other back member and being positioned intermediate the first-mentioned leaf-retaining members, and being shiftable about their pivots to and from their normal parallel relation with the prongs of the other set to permit longitudinal shifting of said leaves and said back members being movable about their hinge connection to a closed position where the prongs on each back member extend across to the other back member, and said back members being movable about said hinge to an intermediate position to permit shifting of said leaves without their removal from the book, and latch means for retaining the back members in said intermediate position.

28. In a loose leaf binder adapted to contain record leaves, a pair of back members, hinge means connecting said back members, a plurality of leaf-retaining members carried by one of the back members and arranged in longitudinally spaced relation, a

plurality of leaf-retaining members independently pivoted on the other back member and being positioned intermediate the first-mentioned leaf-retaining members, and being shiftable about their pivots to and from their normal parallel relation with the prongs of the other set to permit longitudinal shifting of said leaves and said back members being movable about their hinge connection to a closed position where the prongs on each back member extend across to the other back member, said back members being movable about said hinge to an intermediate position to permit shifting of said leaves without their removal from the book, latch means for retaining the back members in said intermediate position, and means under the control of the operator for releasing said latch means.

29. In a loose leaf binder adapted to contain record leaves, two series of impaling prongs, means for mounting and guiding the series of impaling prongs for movement away from each other to permit removal or addition of record leaves, the prongs of one of said sets being obliquely shiftable in two directions from their normal transverse position to vary their position with reference to respective prongs of the opposed set to permit shifting of record leaves with reference to each other.

30. In a loose leaf binder adapted to contain record leaves, two series of impaling prongs, means for mounting and guiding the series of impaling prongs for movement away from each other to permit removal or addition of record leaves, the prongs of one of said sets being obliquely shiftable in two directions from their normal transverse position to vary their position with reference to respective prongs of the opposed set to permit shifting of record leaves with reference to each other, and means for simultaneously shifting all of the prongs of the shiftable set.

31. In a loose leaf binder adapted to contain record leaves, two opposed sets of prongs, the prongs of one set normally extending parallel with the prongs of the other set, means for mounting said sets of prongs for movement away from each other to permit removal or addition of leaves, means for independently pivoting the prongs of one set to permit oblique movement of said pivoted prongs with respect to the prongs of the other set, and means for simultaneously effecting pivotal movement of said pivoted prongs.

In witness whereof I have hereunto set my hand this 12th day of March, 1928.

JOHN L. McMILLAN.
